UNITED STATES PATENT OFFICE.

HENRY A. HILLS, OF GRAND RAPIDS, MICHIGAN.

CONDENSER.

1,256,229.

Specification of Letters Patent. Patented Feb. 12, 1918.

Application filed July 28, 1916. Serial No. 111,908.

To all whom it may concern:

Be it known that I, HENRY A. HILLS, a citizen of the United States, and a resident of the city of Grand Rapids, in the county 5 of Kent and State of Michigan, have invented certain new and useful Improvements in Condensers; and I do hereby declare that the following is a full, clear, and exact description of the same, reference being had 10 to the accompanying drawings, and to the numerals of reference marked thereon, which form a part of this specification.

This invention relates to a condenser particularly designed for use with a distilling 15 apparatus for the condensation and cooling of the volatile products received from a still, although of course well adapted for use in connection with other apparatus wherein a condensing effect is desired.

20 It is an object therefore of this invention to construct a condenser presenting a large condensing surface to an entering vapor with the surfaces so disposed that as the vapor is condensed thereon it flows rapidly by 25 gravity through the condenser, and with a counter-current of a cooling medium to maintain said condensing surfaces cool to not only condense the vapor but to thoroughly cool the same as it proceeds through 30 and leaves the condenser.

It is also an object of this invention to 35 construct a vertical tube condenser provided with a distributing means at the entrance end thereof to direct the vapor to be condensed so that the same flows through the various different tubes, thereby utilizing the full effect of the condenser to condense the vapor and cool the condensates as they leave the condenser.

40 It is furthermore an object of this invention to construct a condenser embracing an upright cylinder and a plurality of tubes extending therethrough and sealed therefrom at the upper and lower ends thereof to admit a flow of vapor into the upper end of 45 said tubes for condensation therein, and with inlet and outlet means in said cylinder to introduce and promote a flow of cooling liquid around said tubes.

50 It is finally an object of this invention to construct an improved type of condenser of large capacity designed to condense and cool a fluid admitted thereto.

The invention (in a preferred form) is

illustrated in the drawings and hereinafter 55 more fully described.

In the drawings:

Figure 1 is a central vertical section with parts in elevation, of a condenser embodying the principles of my invention. 60

Fig. 2 is a section taken on line 2—2 of Fig. 1.

Fig. 3 is a section taken on line 3—3 of Fig. 1.

As shown in the drawings:

The condenser consists of an outer shell 3, which, as shown, is open at its upper end and secured therein are a series of upright condensing tubes 15, all communicating at their upper ends through an apertured plate 70 or head 16, on which there is brazed, riveted, or otherwise tightly secured thereto a conical hood 17, affording a compartment for the vapor to be condensed prior to introduction into the condenser tubes. The outlet pipe 2, 75 from a still is connected into the upper end of said conical hood 17. Within said hood above the plate 16, is a distributing screen or apertured plate 18, shown as rectangular, and acting to insure an even distribution of 80 the entering fluid to the different condensing tubes 15, by passage through the apertures in said plate and dispersion over the edges thereof, between which and the wall of the hood, clearance is provided. The lower 85 ends of said condensing tubes 15, are connected through a crown sheet 19, which is rigidly secured by its flanged periphery to the inner walls of the cylindrical casing 3, of the condenser by riveting, brazing, or 90 otherwise. Connected to said cylindrical casing 3, below said crown sheet 19, is a conical bottom affording a receiving compartment for the condensates into which the discharge pipe 4, is connected. An inlet 95 pipe for cooling water, denoted by the reference numeral 21, is provided, which communicates through the lower end of the cylindrical casing 3, and an outlet pipe 22, is connected at the upper end thereof, so that 100 water admitted into the condenser completely surrounds the condensing tubes 15, flowing upwardly therearound.

The operation is as follows:

The fluid introduced into the condenser 105 through the pipe 2, for condensation strikes the distributing plate 18, and is broken up and caused to spread in different directions

and then passes downwardly for passage through the condenser tubes 15, so that all of said condenser tubes are utilized to condense the fluid. The fluid after condensing in said tubes, flows by gravity downwardly there-through subjected to the cooling action of the liquid surrounding said tubes, so that as the condensate flows outwardly from the condenser it is thoroughly cooled.

10 I am aware that various details of construction may be varied through a wide range without departing from the principles of this invention, and I therefore do not purpose limiting the patent granted otherwise than necessitated by the prior art.

15

I claim as my invention:

1. A condenser comprising an outer cylinder open at its upper end, a crown plate in the lower end of the cylinder, a conical bottom member secured to the cylinder below the crown plate, a plurality of tubes connected to the crown plate, an apertured head plate secured to the tubes, a conical hood secured to the head plate, and a rectangular

apertured distributing plate in said hood 25 having spaces around the edges thereof and the hood.

2. A condenser comprising an outer cylinder, tubes therein, a plate in the bottom of the cylinder through which the tubes open, a 30 member secured to the cylinder below the plate, a plate near the top of the condenser through which the tubes open, a hood secured to the plate, an apertured distributing plate in the hood having a channel between 35 the edge thereof and the hood adapting the fluid to be condensed passing through the distributing plate and diffusing around the edges thereof, and an inlet and outlet pipe opening into the cylinder.

40 In testimony whereof I have hereunto subscribed my name in the presence of two subscribing witnesses.

HENRY A. HILLS.

Witnesses:

CHARLES W. HILLS, Jr.,
EARL M. HARDINE.
